United States Patent Office

Des. 212,416
Patented Oct. 15, 1968

212,416

TRACTOR CANOPY

William F. H. Purcell, Pasadena, Calif., assignor to Deere
& Company, Moline, Ill., a corporation of Delaware

Filed Jan. 9, 1967, Ser. No. 5,353

Term of patent 14 years

(Cl. D14—27)

FIG. 1

FIG. 2

FIG. 1 is a right front perspective view of my new design for a tractor canopy, which is mounted on a tractor, shown in dot-dash lines, for purpose of illustration.

FIG. 2 is a left rear perspective view of the tractor canopy mounted on the tractor which is fragmentarily shown in dot-dash lines.

FIG. 3 is a lower left front perspective view of the tractor canopy alone.

FIG. 4 is an upper left front perspective view of the tractor canopy.

I claim:

The ornamental design for a tractor canopy, substantially as shown and described.
